UNITED STATES PATENT OFFICE.

JAMES ALTON HAZEN AND LOUIS DAVID GENTZLER, OF HOLYOKE, COLORADO.

COLLAPSIBLE CRATE.

1,210,800.

Specification of Letters Patent. Patented Jan. 2, 1917.

Application filed February 24, 1915. Serial No. 10,341.

To all whom it may concern:

Be it known that we, JAMES A. HAZEN and LOUIS D. GENTZLER, citizens of the United States, and residents of Holyoke, in the county of Phillips and State of Colorado, have invented a new and Improved Collapsible Crate, of which the following is a full, clear, and exact description.

This invention relates to improvements in collapsible crates and more particularly to those constructed of metal and more especially designed for use as egg crates.

The primary object of the invention is to provide an improved collapsible egg case in which the component parts thereof are connected in novel relation to be folded so as to occupy a minimum of space for shipment when empty and to be readily set up and closed for shipping purposes, as well as serving to efficiently protect the contents from breakage.

With the above and other objects in view the invention resides more particularly in the peculiar combination and arrangement of parts to be hereinafter more fully described, illustrated and claimed, it being also an object to provide a device which is simple in construction, durable and efficient in operation.

Reference is to be had to the accompanying drawings forming a part of this specification, in which similar characters of reference indicate corresponding parts in all the views and in which—

Figure 1 is a plan view of a collapsible crate constructed in accordance with our invention, the cover thereof being in position to engage the body of the crate; Fig. 2 is a vertical longitudinal sectional view taken on the line 2—2 of Fig. 1; Fig. 3 is a vertical cross sectional view taken on the line 3—3 of Fig. 1; Fig. 4 is a plan view of the body of the crate opened out; and Fig. 5 is a detail perspective view of one of a pair of locking members forming a part of the crate.

As illustrated, the improved collapsible crate or folding egg case comprises a bottom portion 10 of rectangular form in plan, to the front edge of which a front portion 11 is hinged as shown at 12, said front portion having its top edge rolled as shown at 13 and having its end edges provided with tongues 14 bent outward at acute angles with respect thereto, and the ends of the rolled portion 13 or bead 13 and the tongues 14 beveled and spaced apart. To the rear edge of the bot-

tom 10 a back portion 15 is hinged, as shown at 16, the hinge joints being preferably formed by the engagement of coacting tongues of the portions hinged around 60 pintles 17 so that the parts may have pivotal movement relative to each other.

The top edge of the back portion is provided with a rolled edge 18 similar to the front portion, and to the end edges of the back portion 15 end sections or walls 19 are hinged as shown at 19, the top edges of the ends being rolled, as shown at 20, and the free vertical edges thereof being provided with tongues 21 bent at acute angles relative thereto in the same manner as the tongues 14 and adapted to align with the latter when the crate is set up. The bottom edges of the ends 18 are provided with flanges 22 directed at right angles thereto to 70 extend beneath and form supports for the bottom 10, as will be later described.

Secured vertically to the inner faces of the front and back portions are grooved keepers 23, all of the parts as described being preferably constructed of metal and the keepers being bent from sections of metal and soldered or otherwise secured to the inner faces of the front and back portions immediately of the ends thereof. The keepers 23 are provided with entrance slots 24 designed to take a central vertical partition 25 which is provided with oppositely extending rebent or flanged ends 26 engaging the keepers so that the partition may be placed 80 in position or removed vertically in sliding engagement with the keepers.

As thus described the crate may be set up by raising the front and back portions at right angles to the bottom 10 and then swinging the end portions 18 at right angles to the back portion to engage the ends of the bottom and front portions with the flanges 22 extending beneath the bottom. This will cause the tongues 14 and 21 to 90 come together in alignment and the body is then braced by the engagement of locking members 27 with said tongues. These locking members are preferably made slightly heavier than the sheet metal or other material forming the body of the crate and comprise rebent sections of metal with the rebent portions 28 thereof spaced apart as shown at 29 and the ends thereof beveled as shown at 30, while the upper end of each 100 locking member is rolled to provide a grasping portion 31 directed outwardly or in an

opposite direction to the direction of bending of the portions 28. These locking members are slid over the tongues 14 and 21 so as to connect the front and end portions, 5 and the partition 25 is then slid into position to brace the body and divide the same into two compartments of equal size. The body is then closed by a cover 32 having opposite longitudinal beads 33 and a similar bead or 10 bent portion 34 at one end, the other end being smooth and unobstructed. This cover is slid horizontally on to the rolled portions 13 of the front and back portions of the body until the part 34 engages the rolled portion 15 21 of one end member 18, the cover overlying the upper ends of the locking members 27 so as to prevent displacement of the latter. If desired, the top portion or cover 32 and one rolled portion 21 may be provided 20 with apertures 35 through which a wire seal of ordinary form may be passed to prevent unscrupulous opening of the crate during shipment.

The crate may be folded in a compact 25 space by folding the end portions 18 against the inner face of the back portion, folding the bottom portion against the inner face of the front portion and then folding the back portion against the bottom face of the bottom portion, the other positions being laid compactly thereagainst and all bound together if desired.

Having thus described our invention, what we claim as new and desire to secure by Letters Patent is:—

1. A collapsible metal crate, comprising a bottom, a front hinged to the bottom, a back hinged to the bottom, the front and back

having rolled upper edges, ends hinged to the back and having at their lower edges 40 flanges extending under the bottom to support the same, the end edges of the front and the front edges of the ends terminating in outwardly projecting tongues having their inner portions contacting with each other, removable grooved locking members 45 slidingly engaging the said tongues, and each locking member being formed of a flat strip having its edges bent inwardly toward each other and spaced apart, and a cover 50 having longitudinal beads slidably engaging the rolled edges of the front and back.

2. A collapsible metal crate, comprising a bottom, a front hinged to the bottom, a back hinged to the bottom, ends hinged to the 55 back and having at their lower edges flanges extending under the bottom, the end edges of the front and the front edges of the ends terminating in outwardly extending tongues standing at acute angles to said edges and 60 having their inner portions in engagement with each other, removable grooved locking members slidably engaging the said tongues, each member being formed of a flat strip having its edges bent inwardly toward each 65 other and terminating a short distance from one another, and a cover having a sliding engagement with the crate.

In testimony whereof we have signed our names to this specification in the presence 70 of two subscribing witnesses.

JAMES ALTON HAZEN.

LOUIS DAVID GENTZLER.
